Harold M. Davis

UNITED STATES PATENT OFFICE

1,972,194

COIL SUPPORT

Cutler D. Knowlton, Beverly, Mass., assignor to
 Hoague-Sprague Corporation, Lynn, Mass., a
 corporation of Massachusetts

Original application September 8, 1930, Serial No.
 480,518. Divided and this application March
 29, 1932, Serial No. 601,830

14 Claims. (CL 242—76)

My invention relates to means for supporting coils of such material as paper in the form of a ribbon or web, it finding an especially useful field in the apparatus for making box-blanks which is the subject of an application for Letters Patent filed in the United States Patent Office in my name on September 8, 1930 and having the Serial No. 480,518. Of this pending application the present case is a division.

10 In apparatus for manufacturing box-blanks by the continuous-production method, a web of pasteboard or other shell-material is advanced through a series of mechanisms for the performance upon it of various blank-forming operations, and during this travel there may be adhesively attached to it a web of lining-material or a web of cover-material or both, these being commonly of paper. The paper is supplied in a coil, and an object of the present invention is to 15 support and adjust the coil in an effective manner, bringing about its correct delivery to the shell-web or to mechanisms which are to act upon it. To gain this end, I may mount upon a supporting frame spaced arms arranged to carry 20 a coil of web-material and associate with these arms means arranged to move both simultaneously transversely of the web, and I further provide means movable in engagement with each arm and with the frame and arranged to vary the 25 position of each arm independently, as either angularly about a pivotal axis or in the same direction as the simultaneous adjustment. By such an organization, the support may be caused to deliver webs of different widths in such a direction 30 that they will run evenly or without lateral displacement to the point of joining the shell-web or through the apparatus. In the embodiment of the invention disclosed herein, I have employed a sleeve movable longitudinally of a supporting 35 40 spindle and coil-carrying arms movable longitudinally of and angularly about the sleeve. Screws are preferably furnished for effecting gradually the adjustment of the sleeve and the angular adjustment of the arms, and for fixing 45 the arms in the chosen positions. It is desirable to maintain the edges of the convolutions at each extremity of the mounted coil in substantially vertical alignment, to aid in the true delivery of 50 the web from the coil, and for this purpose I may movably mount upon each coil-supporting arm a retaining member, together with means, as a screw, for moving said member. Variable connections, conveniently consisting of a rod secured 55 to the outer ends of the retaining members by

set-screws, are shown for locking said members in the relation thus established.

One of the several forms which my invention may assume is illustrated in the accompanying drawing.

I have shown a fragment of a frame F, which may be that of the blank-making apparatus to which is to be supplied a web of material from a coil W mounted in the following manner: Extending transversely of the frame is a fixed spindle 124, about which may move longitudinally a sleeve 126. Arranged for adjustment upon the sleeve are spaced arms 128, 128 provided with horizontally aligned depressions 130 to receive a spindle 132, about which the coil W of web-material is wound. To hold the opposite edges of the successive convolutions of the coil in the same vertical planes, each arm has an upwardly extending retaining member 134 provided with horizontal guide-rods 136, 136 passing through openings in its arm. Turning in each arm is an adjusting-rod 140, prevented from moving longitudinally by collars 142, 142 secured to the rod upon opposite sides of the arm. At 144, the rod is threaded into the adjacent arm. When either rod 140 is rotated by a hand-piece 146 upon it, the corresponding member 134 may be slid into the desired retaining relation with the sides of the coil of material. Here, both members may be locked by a connecting-rod 148 passing horizontally through openings in their upper extremities and secured by set-screws 150.

It may be desirable, especially in setting up the apparatus, to vary the angular relation of the arms 128 about the sleeve 126. This is useful in so locating the depressions 130 that the coil-spindle 132 will be horizontal, causing the web at its opposite edges to leave the coil in the same direction and thus without distortion. The adjustment is shown as effected by screws 152 threaded through depending portions 153 of the arms and contacting with an element of the frame. After adjustment, the arms may be fixed to the sleeves by set-screws 154. These set-screws also permit a variation in the positions of the arms horizontally of the sleeve, to most advantageously locate said arms for coils which differ in width.

The transverse position of the coil as a whole, and therefore the direction in which the web 105 as a whole runs, is shown as variable by a screw 156 threaded through the frame F and rotatable by a hand-piece 158. A flange 160 upon the screw at its inner end turns between lugs 162 projecting from the adjacent arm 128. Rotation of the screw 110

156 shifts the arm and the sleeve 126, to which it is secured, in one direction or the other, and consequently adjusts across the path of the material the entire coil-supporting structure. This structure is made more rigid for this movement of the entire supporting assembly by the rod 148 tying together the retaining members 134, 134.

Having described my invention, what I claim as new and desire to secure by Letters Patent of the United States is:

1. In combination, a frame, spaced arms mounted upon the frame and arranged to carry a coil of web-material, means common to both arms and arranged to move them simultaneously transversely of the web, and means movable in engagement with each arm and with the frame and arranged to vary the position of said arm independently of the associated arm.

2. In combination, a frame, spaced arms pivotally mounted upon the frame and arranged to carry a coil of web-material, means common to both arms and arranged to move them simultaneously transversely of the web, and means carried by each arm and connecting with the frame and arranged to vary the angular relation of said arm about its pivotal axis.

3. In combination, a frame, a spindle extending transversely of the frame, a sleeve movable longitudinally of the spindle, spaced arms movable upon the sleeve and arranged to carry a coil of web-material, and means arranged to effect the gradual movement of the arms upon the sleeve.

4. In combination, a frame, a spindle extending transversely of the frame, a sleeve movable longitudinally of the spindle, spaced arms mounted upon the sleeve and arranged to carry a coil of web-material, one of the arms being provided with spaced lugs, and a screw threaded through the frame and having a flange lying between the lugs to effect the movement of the sleeve.

5. In combination, a frame, a spindle extending transversely of the frame, spaced arms mounted to turn about the spindle and arranged to carry a coil of web-material, and means for fixing each arm in the position to which it may be moved to control the direction of delivery of the web.

6. In combination, a frame, a spindle extending transversely of the frame, spaced arms mounted to turn about the spindle and arranged to carry a coil of web-material, and a screw threaded through and extending from each arm and bearing at its end against a fixed portion of the frame.

7. In combination, a frame, a spindle extending transversely of the frame, a sleeve movable longitudinally of the spindle, spaced arms mounted to turn about the sleeve and arranged to carry

a coil of web-material, a screw threaded through and extending from each arm for contact with the frame, and a screw threaded through the frame and engaging one of the arms to effect the movement of the sleeve.

8. In combination, a frame, spaced arms pivoted upon the frame and arranged to carry a coil of the web-material, a coil-retaining member movable upon each arm, and means mounted upon each arm and arranged to move the corresponding retaining member.

9. In combination, a frame, spaced arms pivoted upon the frame and arranged to carry a coil of the web-material, a coil-retaining member movable upon each arm, and variable connections between the outer ends of the retaining members.

10. In combination, a frame, spaced arms pivoted upon the frame and arranged to carry a coil of the web-material, a coil-retaining member movable upon each arm, means mounted upon each arm and arranged to move the corresponding retaining member, and variable connections between the outer ends of the retaining members.

11. In combination, a frame, spaced arms pivoted upon the frame and arranged to carry a coil of the web-material, a coil-retaining member movable upon each arm, and a screw rotatable in each arm and threaded into the corresponding retaining member.

12. In combination, a frame, spaced arms pivoted upon the frame and arranged to carry a coil of the web-material, a coil-retaining member movable upon each arm, a screw rotatable in each arm and threaded into the corresponding retaining member, a rod connecting the outer extremities of the retaining members, and set-screws securing the members to the rod.

13. In combination, a frame, spaced arms mounted upon the frame and arranged to carry a coil of web-material, means common to both arms and arranged to move them simultaneously transversely of the path of the advancing web, a coil-retaining member movable upon each arm, and means mounted upon each arm and arranged to move the corresponding retaining member.

14. In combination, a frame, spaced arms mounted upon the frame and arranged to carry a coil of web-material, means common to both arms and arranged to move them simultaneously transversely of the path of the advancing web, a coil-retaining member movable upon each arm, variable connections between the outer ends of the retaining members, and means mounted upon each arm and arranged to move the corresponding retaining member.

CERTIFICATE OF CORRECTION.

Patent No. 1,972,194.

September 4, 1934.

CUTLER D. KNOWLTON.

It is hereby certified that error appears in the printed specification of the above numbered patent requiring correction as follows: Page 2, line 24, claim 2, for "connecting" read contacting; and that the said Letters Patent should be read with this correction therein that the same may conform to the record of the case in the Patent Office.

Signed and sealed this 16th day of October, A. D. 1934.

Leslie Frazer
